UNITED STATES PATENT OFFICE.

HYMAN DIAMOND, OF NEW YORK, N. Y.

SEWING-MACHINE.

SPECIFICATION forming part of Letters Patent No. 615,436, dated December 6, 1898.

Application filed October 24, 1896. Serial No. 609,992. (No model.)

To all whom it may concern:

Be it known that I, HYMAN DIAMOND, a subject of the Czar of Russia, residing at New York, in the county of New York and State 5 of New York, have invented certain new and useful Improvements in Sewing-Machines, of which the following is a full and complete specification, such as will enable those skilled in the art to which it appertains to make and 10 use the same.

This invention relates to sewing-machines; and the object thereof is to provide an improved machine of this class, a further object being to provide means for increasing 15 the speed of the needle or the movement thereof without increasing the speed of the power-shaft or the drive-wheel mounted thereon and for correspondingly increasing the speed or movement of the shuttle and of the mechanism 20 for feeding the fabric beneath the pressure-foot; and with these and other objects in view the invention consists in the construction, combination, and arrangement of parts hereinafter described and claimed.

25 The invention is fully disclosed in the following specification, of which the accompanying drawings form a part, in which similar letters and numerals of reference designate the same parts wherever found throughout 30 the several views, and in which—

Figure 1 is a sectional side view of my improved sewing-machine; Fig. 2, a transverse section thereof on the line 2 2 of Fig. 1; Fig. 3, a bottom plan view of the machine; Fig. 4, 35 a section on the line 4 4 of Fig. 3; Fig. 5, a front view of the front end plate of the machine, which carries the needle-bar, the bar which supports the pressure-foot, and other parts connected therewith; Fig. 6, a back 40 view of said plate; Fig. 7, a longitudinal section thereof on the line 7 7, Fig. 6; Fig. 8, an end view of the arm of the machine and the main power-shaft and parts connected therewith with the front plate removed; Fig. 45 9, a partial section on the line 11 11 of Fig. 1; Fig. 10, a section on the line 12 12 of Fig. 3; Fig. 11, a section on the line 13 13 of Fig. 3; Fig. 12, a perspective view of details of the construction connected with the power-shaft 50 by means of which the speed of the fabric-feeder and of the shuttle are increased without increasing the revolutions of the power-

shaft; Fig. 13, a plan view of a portion of the bottom plate of the machine, showing a sliding plate which covers the shuttle partly removed and showing also a transverse slot in which the feeding device for the fabric works; Fig. 14, a section on the line 16 16 of Fig. 3; Fig. 15, a side view of a detail of the mechanism connected with the power-shaft; Fig. 16, a similar view of another detail of the mechanism connected with said shaft. Fig. 17 is a side view of separate parts of a part of the construction by which the shuttle is operated; Fig. 18, a sectional view of a detail of the construction; Fig. 19, a front view of a lever which forms a part of the mechanism for operating the shuttle-carrier, and Fig. 20 a detail view of two parts of a tension device which forms a part of my improvement. 70

In the practice of my invention, reference being made to Fig. 1 of the drawings, I provide a frame of the usual form, which consists of a base-plate A, the bottom of which is provided with side and end flanges a, and 75 secured to or formed on one end of the base-plate in the usual manner is a hollow upright or standard a², with which the hollow arm a³ is connected. The arm a³ is provided at its outer or free end with a circular head a⁴, above 80 and below which are angular extensions a⁵, and formed in the outer side of the circular head is a circular chamber a⁶.

Passing longitudinally through the arm a³ is a main power-shaft B, on the outer end of 85 which is mounted the drive-wheel b, and mounted on the shaft B, adjacent to the outer side of the hub of the drive-wheel, is a collar b², which is keyed or screwed to said shaft and revolves therewith. This feature of the 90 construction is best shown in Fig. 14, and the drive-wheel b is revolvably mounted on the shaft B, and the collar b² is provided with a spring-operated lug b³, which is adapted to enter a notch or recess b⁴, formed in 95 one side of the hub of the drive-wheel b, and when said lug is located in said notch or recess the drive-wheel will also be keyed to the shaft or to the collar b² and will revolve with the shaft. 100

In practice the shaft B will be operated by a belt or band in the usual manner, said belt or band being mounted on the inner end of the hub of the drive-wheel in an annular

groove b^5 , and I also provide means for revolving said shaft by hand, which comprises a casing b^6 , which is supported by an arm b^7 , which is secured to the standard a^2 or to an arm b^8 , secured thereto or formed thereon, and mounted in the upper part of the casing b^6 , which may be either oblong or circular in form, is a pinion D, the shaft of which extends through the casing b^6 on both sides and is provided at its inner end with a crank-arm d , which is secured thereto and which is provided at its outer end with an inwardly directed or pivoted arm d^2 , which is adapted to enter a slot or opening in the drive-wheel b , and adjacent to the pinion D is mounted a gear-wheel d^3 , to the outer side of which is secured an outwardly-directed arm d^4 , to which is pivoted a crank-lever d^5 , provided with a handle d^6 , and secured to or formed on the outer side of the gear-wheel d^3 opposite the arm d^4 are two outwardly-directed arms d^7 , between which the crank-lever d^5 may be secured, and said crank-lever is provided with a circular opening d^8 , through which the hub d^9 of the gear-wheel d^3 passes, when the said crank-lever d^5 is keyed or locked to the arms d^7 , as shown in Figs. 1 and 14. The operation of this device will be readily understood, and it will be apparent that when the gear-wheel d^3 is revolved by the crank-lever d^5 the pinion D will turn the crank-arm d and said crank-arm will turn the drive-wheel b , and said drive-wheel being locked or keyed to the shaft B by the spring-operated lug b^3 the shaft B will also be revolved.

The object of connecting the crank-lever d^5 with the gear-wheel d^3 in the manner described is simply to provide means for folding said crank-lever d^5 , so that the handle d^6 will project in the opposite direction in order that this device may be packed in a small space when necessary, and instead of employing said crank-lever d^5 any other suitable means may be provided for operating the gear-wheel d^3 , and the object of revolubly mounting the drive-wheel b on the power-shaft B is to provide means whereby in the operation of winding the bobbin, as herein-after described, the power-shaft will not be operated.

Mounted on the power-shaft B within the upper portion of the standard a^2 is a collar C, a side view of which is given in Fig. 16, and mounted on said shaft adjacent to said collar 55 is a triangular block C^2 , and both the collar C and the triangular block C^2 are keyed to or formed on the shaft B, and the corners of the block C^2 project to the perimeter of the collar C, and the triangular block C^2 may be 60 formed on and constitute a hub for the collar C, if desired, and mounted on said shaft adjacent to the triangular block C^2 and a short distance therefrom is another collar C^3 , which is shown in detail in Fig. 15, and the collar C^3 is also keyed to the shaft B, and secured to or formed on the perimeter thereof at equal 65 distances apart are three buttons or knobs

C^4 , these features of construction being best shown in Figs. 1, 2, 12, 15, and 16.

Mounted in the standard a^2 is a lever E, which is provided centrally with a transverse hub E^2 , through which passes a short bolt E^3 , provided with a head E^4 and a screw-threaded extension E^5 . This construction is best shown in Figs. 9, 12, and 18, and formed on the inner side of the wall of the standard a^2 is a shoulder or projection E^6 , and a corresponding shoulder or projection E^7 is formed on the outer side of said wall, and passing centrally through said wall and said shoulders or projections is a screw E^8 , provided with a head E^9 , and mounted on the screw E^8 is a screw-threaded collar F, and the inner end of the screw E^8 is provided with a collar F^2 , and the screw-threaded extension E^5 of the bolt E^3 passes into the end of the screw E^8 , as clearly shown in Fig. 9.

The hub E^2 of the lever E is provided with a central bore, the ends of which are enlarged at the upper and lower sides, as clearly shown in Fig. 18, and said lever is therefore free to oscillate transversely of the standard a^2 , and the upper end thereof is curved in form and bears upon the triangular collar or block C^2 , which is mounted on the shaft B and by which said lever E is operated, and the lower end of the lever E is pivotally connected with a link or bar G, Fig. 12, which is pivotally connected with a crank g , which is secured to or formed on a shaft g^2 , which is pivoted at g^3 to hangers of the base-plate and extends longitudinally of the base-plate A of the frame and within one of the side flanges a below said base-plate.

Secured to or formed on the shaft g^2 at predetermined distances from the ends thereof are two cranks or arms g^4 , between which is pivoted a shaft g^5 by means of pivot-pins g^6 , and the shaft g^5 is provided with arms g^7 and g^8 , which project inwardly beneath the base-plate A of the frame, and the arm g^8 at the rear end of the shaft g^5 is provided at its inner end with a knob or projection g^9 , which is secured thereto and which projects at right angles therefrom in the direction opposite to that of the lever E, and the other arm g^7 , which is secured to or formed on the shaft g^5 , is rigidly connected at its free end with a downwardly-directed arm h of the fabric-feeder H, which is mounted in a transverse slot h^2 in a plate h^3 , as shown in Fig. 13, the downwardly-directed arm h being formed on or secured to one end of said feeder H and said feeder being longitudinally movable in the slot or opening h^2 in the usual manner.

Mounted centrally of the bottom of the base-plate A of the frame, Fig. 3, is a depending pin K, on which is mounted a sleeve k, which is provided at one side with two similar segmental plates k^2 , which are best shown in Figs. 3 and 11 and between which is a cam-track k^3 , into which the knob or projection g^9 on the arm g^8 passes, Fig. 11, and the sleeve k is also provided with an arm k^4 , which pro-

jects therefrom at right angles to the segmental plates k^2 and in the direction opposite to that of the shafts g^2 and g^5 .

The lower end of the lever E passes through a slot k^5 in the base-plate A of the frame, as shown in Fig. 3, and secured to said base-plate adjacent to said slot and on the side thereof adjacent to the shaft g^2 is a stop k^6 , and I also provide a spring k^7 , which is secured to the bottom of the base-plate A and the end of which bears upon the lower end of the lever E opposite the bearing k^6 , and said spring is adapted to force the lower end of the lever E in the direction of the shaft g^2 .

The lever E is designed to operate the fabric-feeder H, and I also provide a lever L, which is intended to operate the shuttle-carrier, as hereinafter described. Said lever L is shown in detail in Fig. 19, also in Fig. 12, 20 and in Figs. 1, 2, and 9. This lever is provided centrally with a transverse hub L^2 , which is best shown in Figs. 9 and 12, and passing through said hub is a bolt L^3 , which is screwed into and through a hub L^4 , formed 25 on the inner side of one side of the standard a^2 and also through the side of the standard, as clearly shown in Fig. 9, and the body portion of the bolt L^3 , which passes through the hub L^2 , is of the form shown in dotted lines 30 in Fig. 9, and said hub is securely held thereon and free to turn thereon, and this lever is adapted to oscillate longitudinally of the arm a^3 .

The upper end of the lever is provided with 35 a triangular head L^5 , in connection with which the collar C^3 on the shaft B operates, and the side of said head adjacent to said collar is concave transversely, as shown at L^6 in Fig. 2, and at the upper and lower sides thereof are notches or recesses L^7 and L^8 , through 40 which the buttons or knobs C^4 on the collar C^3 pass in the operation of the machine, as hereinafter described, and the said triangular head L^5 is convex in vertical section on 45 its outer side, and formed therein is an angular slot L^9 , the ends of which are both directed toward the drive-wheel b and the central portion in the opposite direction or toward the support of the needle, and the ends 50 of said slot are separated by a triangular projection L^{10} .

The lower end of the lever L passes through a slot M in the base-plate A at the lower end of the standard a^2 and is provided, as shown 55 in Fig. 12, with an outwardly-directed pin m , on which is mounted an open sleeve or band m^2 , with which is pivotally connected a rod m^3 , said connection of the rod m^3 being made by means of a collar m^4 , to which is secured 60 a thin flexible tongue m^5 , and the opposite end of the rod m^3 is pivotally connected in the same manner with the arm k^4 of the sleeve k , on which the segmental plates k^2 are formed, as shown at 25 in Fig. 3, and 65 pivotally connected in the same or in any preferred manner with the end of the arm k^4 at 26 is a rod m^6 , which is pivotally connected

at 27 with an arm m^7 , which is connected with or formed on a sleeve m^8 , which is mounted on a pin m^9 and held in place by a nut or 70 bur m^{10} , said pin being secured to the base-plate A of the frame, and connected with the opposite end of the arm m^7 in any desired manner is a shuttle-carrier N. These features of the construction are best shown in 75 Figs. 3, 12, and 17, and the shuttle-carrier N moves in a segmental or circular track n beneath a longitudinal slot n^2 , formed in a plate n^3 , secured to the base-plate A of the frame, this feature being substantially the same as 80 usual, with the exception of the segmental track n, in which the shuttle-carrier N travels.

The shuttle n^4 is mounted in the shuttle-carrier N in the usual manner and is of the usual form, and pivoted to the flange a on 85 the under side of the base-plate A and adjacent to the outer end of the track n is an arm n^5 , which is best shown in Fig. 4, and said arm projects inwardly along the segmental flange n^6 on the convex side of the 90 track n, in which the shuttle-carrier moves, and said arm is provided at its inner end with a depending extension n^7 , on which is formed an inwardly and upwardly directed hook n^8 , and the pivoted end of the arm n^5 is provided 95 with an upwardly-directed projection n^9 , which fits in a slot O^2 , formed in the under side of the sliding plate O and adjacent to one edge thereof. The sliding plate O is adapted to cover the slot n^2 in the plate n^3 in 100 the usual manner, and said slot or opening n^2 is intended for the insertion and removal of the shuttle, and in practice all that is necessary in order to remove the shuttle is to pull the plate O outwardly, as shown in Figs. 105 4 and 13, when the upwardly-directed projection n^9 on the arm n^5 will strike the inner end wall of the slot O^2 and throw up the free end of the arm n^5 , and in this operation the hook n^8 at the end of said arm will throw the 110 shuttle n^4 out through the slot or opening n^2 .

Mounted on the end of the shaft B which projects into the head a^4 at the end of the arm a^3 is a circular block P, provided with a hub P^2 , which projects into a corresponding 115 opening formed in the end of the arm a^3 , and formed in the outer side of the circular block P, which is keyed or otherwise secured to the shaft B and revolves therewith, is a slot P^3 , the general form of which is triangular, as 120 shown in Fig. 8, the sides of the triangle being inwardly curved, as shown at P^4 , while the corners thereof are cut away, as shown at P^5 , the slot P^3 being thus provided with three short sides and three long sides, the 125 long sides being inwardly curved or bent.

Pivotally connected with one side of the circular head a^4 is a lever P^6 , which extends across said head and across the block P and which is provided with an inwardly-directed 130 lug P^7 , which moves in the slot P^3 and the free end of which is provided with a curved rod P^8 , which is pivotally connected therewith at P^9 and the upper end of which is

pivotedly connected at R with an arm R², which is secured to the vertically-movable needle-bar R³, which is mounted in the front plate R⁴, which is secured to the head a⁴.

5 The upper end of the needle-bar R³ is provided with a vertical slot R⁵, through which projects a lever R⁶, mounted in a vertical slot R⁷, formed in the upwardly-directed extension a⁵ of the head a⁴, and the lever R⁶ is pivoted on a pin R⁸, which is provided with a spring R⁹, one end of which is secured to the pin R⁸ and the other passed through the lever R⁶ at R¹⁰, and the object of this spring R⁹ is to throw the lever R⁶ upwardly, and the upper end of the slot R⁵ in the needle-bar R³ is curved, as shown in Fig. 7, so as to correspond with the form of the lever R⁶, the form of which is shown in full and dotted lines in Fig. 1.

20 The front plate R⁴ is provided in front of the needle-bar R³ with a vertical slot S, through which the spring-operated lever R⁶ passes, and in practice the thread 28 is carried from the spool through a hook or similar device S², which is secured to or formed on the side of the front plate R⁴, as shown in Fig. 1, and then passed around the tension device S³, and then carried upwardly and passed through the end of the lever R⁶ and downwardly 25 through a keeper S⁴, secured to the front plate R⁴, and then through another keeper S⁵, secured to the lower end of the needle-bar.

The tension device S³ is shown in Figs. 1, 5, 6, and 7 and is of the following construction: Formed centrally of the back of the front plate R⁴ is a vertical slot S⁶, in which moves an arm S⁷, formed on a plate S⁸, secured to the vertically-movable pressure-foot bar S⁹, which is mounted in the front plate R⁴ 30 in the usual manner, and passing through said front plate R⁴ in line with the slot S⁶ is a screw-threaded bolt T, in the inner end of which is mounted a sliding pin T², and mounted on the bolt T adjacent to the front plate R⁴ is a disk T³, the perimeter of which is beveled on its outer edge, and adjacent thereto is a similar disk T⁴, the perimeter of which is beveled on its inner edge, and the disks T³ and T⁴ are free to slide on the bolt S, and adjacent to the disk T⁴ is mounted a washer T⁵, and the outer end of the bolt T is provided with an adjustable screw-threaded nut T⁶, and between the nut T⁶ and the washer T⁵ is a spiral spring T⁷.

55 The construction of the bolt T and the washer T⁵ is shown in detail in Fig. 20, and the central opening in the washer T⁵ is provided with a transverse bar T⁸, which passes through the slot T⁹ in the bolt T, while the pin T² moves in a longitudinal central bore T¹⁰, formed in the inner end of the bolt T and which communicates with the slot T⁹.

60 The arm S⁷ of the plate S⁸ is concave longitudinally on the inner side thereof, and as the pressure-foot bar S⁹ moves up and down the pin T² will be forced outwardly or inwardly, as the case may be, said pin being forced out-

wardly by the arm S⁷ and inwardly by the spring T⁷, and the thread is passed between the disks T³ and T⁴, and when the pressure-foot bar is raised preparatory to removing the fabric from beneath the pressure-foot u the pin T² will be forced outwardly and with it the disk T⁴, and the tension on the thread will be released and the same may be easily pulled downwardly or loosened in the usual manner.

65 The back of the front plate R is cut away between the points u² and u³, so as to provide room or space for the lever P⁶, the rod P⁸, and the plate S⁸, and the arm R², and mounted on the pressure-foot bar S⁹, above the plate S⁸, is a spiral spring u⁴, which is intended to hold the pressure-foot bar in its lowest position, and the tension of this spring is regulated by 70 a screw u⁵, which is mounted on the upper end of the pressure-foot bar and which enters the upper end of the front plate R⁴, and the upper end of the needle-bar is also provided with a central bore, into which passes a screw u⁶, which is adapted to limit the upward movement of the lever R⁶, and pivotally connected with the outer side of the front plate R⁴ and near the bottom thereof is a lever u⁷, which is adapted to operate in connection with a lug or projection u⁸, formed on or secured to the pressure-foot bar and passing through a slot u⁹ in the front plate, the object of said lever being to raise the pressure-foot bar in the usual manner, said pressure-foot bar being held in the depressed position by the spring u⁴ and in the raised position by said lever u⁷.

75 The needle W is detachably connected with the needle-bar R³ in the usual or any preferred manner and passes through a slot formed in the pressure-foot u, and the operation thereof, in connection with the shuttle n⁴, is the same as in other machines of this class.

80 The operation of this form of construction will be readily understood from the foregoing description when taken in connection with the accompanying drawings and the following statement thereof: The shaft B may be 85 revolved in any desired manner, either by a belt mounted in the groove b⁵ in the hub of the drive-wheel b or it may be operated by the crank-lever d⁵, and at each revolution of the drive-shaft B the lever E will be given 90 three successive oscillations by means of the triangular block C² on said shaft, and the lower end of this lever being in connection, as hereinbefore described, with the fabric-feeder H by means of the parts G, g², and g⁵ 95 said fabric-feeder will also be given three complete reciprocations or three back-and-forth movements. The slot k³ between the segmental plates b², in which the knob or head g⁹ on the arm g⁸ moves, is upwardly inclined 100 in the direction of said arm, and by means of this construction the arms g⁷ and g⁸ being rigidly secured to the shaft g⁵ the fabric-feeder H will move downwardly on its back- 105

ward movement and upwardly on its forward movement, thus operating to grip and release the fabric in the proper time. The shuttle-carrier and shuttle are operated at the same time by means of the lever L, and at each revolution of the shaft B the said lever is given three complete oscillations longitudinally of the arm of the machine, this result being accomplished by means of the buttons or knobs C⁴ on the collar C³, which operate in the slot L⁹ of the head L⁸ of said lever, and the lower end of this lever being connected, as herein described, with the arm m⁷, by which the shuttle-carrier is supported and operated, said shuttle will also be given three complete reciprocations or three back-and-forth movements in the race n. The movements of the shuttle and of the fabric-feeder H are thus made to correspond and the movement of the needle-bar and the needle is regulated in the same manner by means of the groove P³ in the circular head P, which is mounted on the end of the main shaft B, said result being accomplished by means of the lug or projection P⁷ on the lever P⁶, which moves in the groove P³, said lever being in connection by means of the rod P⁸, which is pivotally connected therewith, and the arm R² with the needle-bar, and by means of this construction at each revolution of the shaft B the needle-bar R⁸ will be given three complete reciprocations or three up-and-down movements, and the operations of the shuttle, the needle, and the fabric-feeder are all thus made to correspond, and at each revolution of the power-shaft three stitches will be made.

My improved machine is simple in construction and operation, and my invention is not limited to the means herein shown and described for connecting the lever L, the rod m³, the arm k⁴, the rod m⁶, and the arm k⁷, any suitable pivotal connection being sufficient, and the same is also true of the means for connecting the lever E, the arm G, the shaft g², the shaft g⁵, and the arms g⁷ with the fabric-feeder, as various devices may, as will be understood, be adopted for this purpose.

Having fully described my invention, I claim as new and desire to secure by Letters Patent—

1. A sewing-machine provided with a power-shaft, and means for revolving the same, a curved track, a shuttle-carrier which is adapted to move in said track, an arm connected therewith, and pivotally supported, a lever pivotally mounted in the upright standard of the machine by which the main arm thereof, is supported, a collar mounted on the power-shaft, and provided with a plurality of lugs or projections which are adapted to operate in an angular or irregular slot, formed in the head of said lever, and operative devices connected with the lower end of said lever, and with the arm of the shuttle-carrier whereby the shuttle-carrier is given a plurality of

movements for each revolution of the power-shaft, substantially as shown and described.

2. A sewing-machine provided with a power-shaft and means for revolving the same, a curved track, a shuttle-carrier which is adapted to move in said track, an arm connected therewith, and pivotally supported, a lever pivotally mounted in the upright standard of the machine by which the main arm thereof is supported, a collar mounted on the power-shaft, and provided with a plurality of lugs or projections which are adapted to operate in an angular or irregular slot formed in the head of said lever, and operative devices connected with the lower end of said lever, and with the arm of the shuttle-carrier, whereby the shuttle-carrier is given a plurality of movements for each revolution of the power-shaft, and a fabric-feeder and needle-bar and devices connected with said fabric-feeder and needle-bar and with the power-shaft for correspondingly increasing the movements of said needle-bar and fabric-feeder, substantially as shown and described.

3. A sewing-machine provided with a power-shaft and means for revolving the same, a collar mounted thereon, and provided with a plurality of sides, a transversely-oscillating lever pivotally supported in a hollow standard by which the arm of the machine is supported, and the upper end of which operates in connection with said collar, and the lower end of which passes through the base-plate of the machine, a fabric-feeder connected with the lower end of said lever by means of an arm pivotally connected with said lever and with a longitudinal shaft mounted below the base-plate and provided with upwardly-directed arms between which is pivoted another shaft, said last-named shaft being provided with an arm which is connected with the fabric-feeder whereby said fabric-feeder is given a plurality of movements for each revolution of the power-shaft, and a needle-bar and shuttle-carrier; and devices connected therewith, and with the power-shaft for giving said needle-bar and shuttle-carrier a corresponding plurality of movements for each revolution of the power-shaft, substantially as shown and described.

4. A sewing-machine provided with a power-shaft and means for revolving the same, a curved track, a shuttle-carrier which is adapted to move in said track, an arm connected therewith, and pivotally supported, a lever pivotally mounted in the upright standard of the machine by which the main arm thereof, is supported, a collar mounted on the power-shaft, and provided with a plurality of lugs or projections which are adapted to operate in an angular slot formed in the head of the lever, and operative devices connected with the lower end of said lever, and with the arm of the shuttle-carrier whereby the shuttle-carrier is given a plurality of movements for each revolution of the power-shaft, and a

fabric-feeder connected therewith, and with the power-shaft, and with the operative mechanism of the shuttle-carrier for giving said fabric-feeder a corresponding plurality of movements, substantially as shown and described.

In testimony that I claim the foregoing as

my invention I have signed my name, in presence of the subscribing witnesses, this 19th day of October, 1896.

HYMAN DIAMOND.
